UNITED STATES PATENT OFFICE.

BORIS V. LOUTZKOY, OF ANDREEWKA, RUSSIA.

AIR-CUSHION HUB.

1,426,886.

Specification of Letters Patent. Patented Aug. 22, 1922.

Application filed May 12, 1920. Serial No. 380,946.

To all whom it may concern:

Be it known that I, BORIS VON LOUTZKOY, Diplom-Engineer, a subject of Russia, and residing at Andreewka, Gouvernement Tau-rien, Russia, have invented certain new and useful Improvements in Air-Cushion Hubs, of which the following is a specification.

The present invention relates to resilient wheels of the pneumatic type wherein cylinders and pistons are used with pivoted links connecting either the cylinders or the pistons to the rim or the hub of the wheel to permit of the desired eccentric movement of the rim relatively to the hub.

An object of the present invention is to provide means for limiting the swinging movements of the links to prevent the same from moving into a dead center or locking position and to strengthen the wheel structure and prevent damage thereto or movements beyond the range of efficiency.

Another object of the invention is to provide guiding or stopping means of this character which permits the free operation of the links within the desired limits and which securely hold the links after their motion has been arrested.

The above and various other objects and advantages of this invention will be in part, described in, and in part understood from, the following detailed description of the present preferred embodiment, the same being illustrated in the accompanying drawings, wherein—

Fig. 1 is a diagrammatic view of a wheel constructed according to this invention and having the stops and guides applied thereto, the parts of the wheel being shown in position when the wheel is in use;

Fig. 2 is a similar view showing the positions of the parts when the wheel has been at rest for a considerable length of time; and

Fig. 3 is a fragmentary section through a wheel taken in the plane thereof and showing parts in section, and illustrating the improvements of this invention applied thereto.

Fig. 4 is a transverse section through the casing at one of the cylinders, showing the connections and stops.

Referring to the drawing, *m* designates a hub about which is arranged a rim member or casing *n*. This casing *n* is made up of a relatively broad ring *s* and lateral annular plates *t* extending inwardly from the opposite edges of the ring *s*. The casing *n*

may form the outer portion of the hub and be connected by spokes or the like to an outer rim. The hub *m* carries a plurality of radially extending pistons *a* over which are fitted a corresponding number of cylinders *b*. The cylinders *b* are provided with pins *o* at opposite sides upon which are pivoted links *c*.

The free ends of the links are mounted on pins *p* which project inwardly from the sides of the casing *n* for supporting the casing or rim upon the cylinders *b*. The rim *n* is adapted to move relatively to the hub *m* into different eccentric positions and the links *c* are adapted to swing through various arcs to follow their pivots *p*.

When submitted to abnormal shocks or load there is a tendency for the links *c* to swing through a greater arc than is defined by an obtuse angle relatively to its normal position and consequently there is liability of the links at opposite sides of the hub becoming locked or passing on to dead center.

To obviate this excess swinging of the links, stops *f* are provided and are preferably in the form of shoulders or hooks rolled over on the opposite ends of guides *d*. The guides *d* may be in the form of metallic plates curved on an arc struck from the fixed pivot *o* of the adjacent link to follow the path of the movable pivot *p*. The plates *d* may be secured to the opposite sides of the cylinders *b* toward the inner ends thereof and project laterally from the cylinders to receive therein the pivots *p* which extend from the rim or casing *n*.

It is apparent that when the link *c* swings in either direction to the limit of its movement, the pin or end of the link strikes the adjacent shoulder *f* and is stopped from further swinging and is held by the hook rigidly in place.

What is claimed is:

1. In a pneumatic cushioned wheel, the combination of a hub, a rim member, a plurality of pistons extending radially from the hub, cylinders fitting on the outer ends of the pistons, and links connecting the cylinders to the rim member, guides for the links, said guides being carried by the cylinders and adapted to embrace the ends of the links that are connected to the rim member, the guides having stops at opposite ends to limit the swinging of the links in opposite directions about their pivots in the cylinders.

2. In a pneumatic cushioned wheel, a hub, a rim member, and a plurality of spokes connecting the hub and the rim, each of said spokes comprising a piston carried by the hub and a cylinder slidable on the piston, a link pivotally connecting the cylinder to the rim, and guides carried upon the cylinder having stop shoulders at opposite ends

adapted to engage the link and limit the swinging thereof in opposite directions. ¹⁰

In testimony whereof I affix my signature in presence of two witnesses.

BORIS v. LOUTZKOY.
